CLAIM

The ornamental design for a cosmetics bottle, as shown and described.

DESCRIPTION

FIG. 1 is a top perspective view of a first embodiment of a cosmetics bottle according to our new and ornamental design;

FIG. 2 is a bottom perspective view thereof;

FIG. 3 is a front elevation view thereof, wherein the rear elevation is identical;

FIG. 4 is a left side elevation view thereof, wherein the right side elevation is identical;

FIG. 5 is a top plan view thereof;

FIG. 6 is a bottom plan view thereof;

FIG. 7 is a top perspective view of a second embodiment of a cosmetics bottle according to our new and ornamental design;

FIG. 8 is a bottom perspective view thereof;

FIG. 9 is a front elevation view thereof, wherein the rear elevation is identical;

FIG. 10 is a left side elevation view thereof, wherein the right side elevation is identical;

FIG. 11 is a top plan view thereof; and,

FIG. 12 is a bottom plan view thereof.

The broken lines represent portions of the cosmetics bottle that form no part of the claimed design.

1 Claim, 12 Drawing Sheets
